UNITED STATES PATENT OFFICE.

GEORGE H. VAN ECK, OF TAMPA, FLORIDA.

FLUSH BOWL.

Application filed March 18, 1921. Serial No. 453,270.

To all whom it may concern:

Be it known that I, GEORGE H. VAN ECK, a citizen of the United States, residing at Tampa, in the county of Hillsborough and 5 State of Florida, have invented certain new and useful Improvements in Flush Bowls, of which the following is a specification.

This invention relates to flush tanks, and the primary object of the invention is to provide a novel type of flush tank in which a sufficient quantity of water may be maintained therein, so that the bowl can be flushed a number of times, in case the supply of water to the tank is cut off from any 10 cause, such as during repairs to the water mains or when the mains are cut off during extraordinary cold weather in the water system of cities or the breaking down of the wind mill or other pumping apparatus in individual systems.

Another object of the invention is to provide an improved flush tank in which a sufficient quantity of water can be maintained for permitting a bowl to be flushed a number 15 of times, which is so constructed that only a sufficient quantity of water will be permitted to flow from the tank during each actuation of the valve outlet therefor, thereby preventing the entire rush of water from the tank 20 each time the outlet valve is operated.

A still further object of the invention is to provide a novel flush tank of the above character, which will be durable and efficient in use, one that will be simple and easy to 25 manufacture, and one which can be used with ordinary bowls now on the market.

With these and other objects in view, the invention consists in the novel construction, formation and arrangement of parts as will 30 be hereinafter more specifically described, claimed and illustrated in the accompanying drawings, forming a part of this specification, in which drawings:

Figure 1 is a vertical longitudinal section through the improved flush tank.

Figure 2 is a vertical transverse section through the improved flush tank, and

Figure 3 is a horizontal longitudinal section on a smaller scale, taken on the line 3—3 50 of Figure 1.

Referring to the drawings in detail, wherein similar reference characters designate corresponding parts throughout the several views, the letter A generally indicates the improved flush tank, which as 55 shown is constructed of vitreous material,

although it is to be understood that the same can be made of wood and provided with the usual metal lining if so desired. The flush tank can also be of the overhead or low down 60 variety and is so formed as to hold a relatively large quantity of water, say three or four times the usual amount, so that sufficient water can be always maintained in the tank to permit the flushing of the bowl a 65 number of times in case the supply of water to the tank is temporarily cut off from any cause. The tank A as shown includes the front wall 5, the rear wall 6, the end walls 7, the bottom wall 8 and the removable top 70 wall or plate 9.

The tank A is divided into an upper compartment 10 and a lower compartment 11 by means of a horizontally disposed partition 12, and the compartment 11 is adapted 75 to just hold a sufficient quantity of water to flush a bowl once, while the upper compartment 10 is adapted to hold sufficient water for a number of flushings.

The partition 12 can be of any desired 80 construction, but it is preferred that the same include a longitudinally extending ledge 13 connected to or carried by the front wall 5 and the end walls 7. The inner edge of the partition 13 is adapted to be rabbeted 85 as at 14 for forming a seat for the removable plate 15, which also forms a part of the partition. The partition plate 15 is freely removable so as to permit access to be readily had to the outlet valve mechanism 16 which 90 is of the ordinary or any preferred construction in order to permit repairs and the like to be made thereto. The rear wall 6 can be provided with longitudinally extending 95 spaced ribs 17 for receiving the rear longitudinal edge of the plate 15 for holding the same in position. In placing the plate 15 in position the rear edge thereof is inserted between the retaining ribs 17 and then swung downwardly on the rabbeted portion 14 of 100 the ledge 13 and if so desired suitable pivoted retaining members 18 can be provided to overlie the partition plate 15 to hold the same in position against accidental displacement. The partition 15 is provided with a 105 relatively small opening 17', through which the water is adapted to flow from the reservoir compartment 10 to the lower compartment 11.

As heretofore stated, the outlet valve 16 110 is of the usual construction, and is adapted to operate in the ordinary manner and the

valve is connected to the operating crank 19 by means of the connecting rod 20 and this crank 19 can be operated by a suitable chain and pull 21. It is to be understood, however, 5 that I do not limit myself to the particular valve and operating means therefor, as it can be readily understood that any suitable valve and operating means can be employed without interference with my invention.

10 The ledge 13 is provided with the upstanding pipe 22, through which the connecting rod 20 extends and this pipe serves as a guide and protector for the rod 20. It also can be seen that the water in the compartment 11 will be permitted to flow up in the pipe 22 until the same reaches the level of the water in the compartment 10.

15 The water is supplied to the tank through the ordinary inlet valve mechanism 24, 20 which is controlled by the ordinary float mechanism 25. This forms no portion of the present invention, however, and any type of inlet valve and automatic cut off can be employed.

25 In operation of the improved tank, it can be seen that when the outlet valve mechanism 16 has been actuated, the water will be permitted to flow from the lower compartment 11 through the outlet pipe to the bowl, 30 and the valve will be automatically held off of its seat in the ordinary manner, by the rush of water from the compartment through the outlet pipe. The flow of water from the reservoir 10 through the opening 17' is so 35 light that the same will not interfere with the seating of the outlet valve upon its seat after the flow of water from the lower compartment 11, but this opening is of sufficient size to permit the compartment 11 to be filled 40 after the valve has resumed its normal position.

It can be seen that if the supply of water is cut off from the tank for any cause, there will be sufficient water in the tank for permitting the bowl to be flushed a number of 45

times. This forms an exceedingly simple construction and is a long felt want in communities having private water systems which are liable to breakage, or in city water systems where at certain periods the water 50 is temporarily cut off during cold spells.

Changes in details may be made without departing from the spirit or scope of my invention; but,

I claim:

1. A flush tank arranged to hold a sufficient quantity of water to permit a bowl to be flushed a number of consecutive times, a horizontally disposed partition arranged in the tank dividing the same into upper and lower compartments, outlet valve mechanism arranged in the lower compartment, inlet valve mechanism arranged in the upper compartment, means for permitting communication between said compartments, a portion 60 of said partition at one side of the outlet valve mechanism being formed removable to permit access to be had to said outlet valve mechanism.

2. A flush tank arranged to hold a sufficient quantity of water to permit a bowl to be flushed a number of consecutive times comprising a horizontally disposed partition arranged therein dividing the tank into an upper and a lower compartment, the partition including a longitudinally extending flange carried by one longitudinal wall of the tank, retaining ribs arranged in direct alignment with the flange and carried by the opposite longitudinal wall, a removable partition plate arranged to engage the ribs and said flange, means to hold the partition plate against accidental movement, a port formed in said partition plate, an outlet valve including a connecting rod, and a pipe carried 70 by the flange arranged to receive said connecting rod, said pipe and rod being disposed at one side of the removable partition plate.

GEORGE H. VAN ECK.
